UNITED STATES PATENT OFFICE

ERNEST J. SWEETLAND, OF HAZLETON, PENNSYLVANIA

DISPENSING MACHINE

Application filed May 21, 1927. Serial No. 133,136.

This invention relates to improvements in receptacles for temporarily holding articles of a nature that are adversely affected by exposure to moisture, air, and the like, and 5 means for dispensing these articles.

There are many articles such as tobacco, granulated or powdered materials, and others that are affected adversely by either too much humidity or moisture in the air or are affected 10 by too little moisture and dry out. For example, sugar or salt or malted milk or other food products may be spoiled or become hardened and unfit for use if they become unduly damp. Tobacco on the other hand, 15 should be kept reasonably moist for most satisfactory conditions. All of these articles and many other similar ones should also be kept free from contaminating dust and dirt.

It is, therefore, the principal object of this 20 invention to provide a receptacle for various articles of the class described to keep them under regulated atmospheric conditions.

It is another object of this invention to provide a means for temporarily containing 25 various dry products for subsequent dispensing which may retain the products in a substantially air tight condition.

It is still another object of this invention to provide a substantially hermetically sealed 30 container which is provided with a dispensing means that does not break the air seal and dispenses measured unit quantities from the contents of the container.

It is a further object of this invention to 35 provide a means for regulating the moisture content of a substantially dry product by enclosing it in a sealed container.

It is a still further object of this invention 40 to produce a receptacle for the principal purpose of effectively storing small quantities of products that may be temporarily retained for future dispensing, the relative amount of which may be quickly determined by inspection.

45 Further objects and advantages of this invention will appear from the following description of the accompanying drawings which illustrate certain preferred forms of embodiment to which this invention is adaptable and in which:

Fig. 1 is a side elevation, partly in section of a container produced in accordance with my invention.

Fig. 2 is another view of the device shown in Fig. 1.

Fig. 3 is a top plan view of Fig. 1.

Fig. 4 is a side view partly in section of a modified form of dispensing means.

Fig. 5 is a partial elevation, partly in section of a machine similar to Fig. 1 showing a different use of the same.

Fig. 6 is a vertical section of a still further modified form of dispensing means for liquid articles.

The dispensing machine shown in Figs. 65 1 and 2 is particularly adapted to dispense tobacco. It comprises the base 10, a transparent dome or reservoir 12 which is filled through the filling cap 14 and the dispensing means 16 through which the material is suitably removed. The base which is preferably made of metal is substantially cylindrical in cross section although a suitable flare to the bottom portion 10^a permits a more rigid supporting structure. The base is vertically divided near the middle thereof by a horizontal web 10^b in which the filling cap 14 is fitted by a screw thread. It will be apparent from Fig. 1 that the flared bottom portion 10^a will thus act as a funnel or guide to the filling material and will advantageously aid in the filling operation.

The dome or reservoir 12 which is preferably glass is generally cylindrical in shape and is superposed by a hemispherical top. 85 At the bottom it is adjoined to the base portion in any suitable manner and retained by a material such as the permanent plaster of Paris or cement 12^a. The cement will prevent accidental displacement of the dome as well as seal it from the atmosphere. This dome or reservoir is made of a transparent glass in order that the enclosed material may be clearly seen. It is possible, however, to make it out of porcelain or metal or any other 90 preferred material.

The dispensing means 16 consists of a tubular shell attached in some manner such as by a screw thread, to an appropriate opening in the base 10, above the web 10^b and 100

inside the chamber. A screw 17 or worm within this tubular shell, operated by any means such as a knurled knob 18 will efficiently remove the material through the tube and dispense it from the discharge spout 19. This spout is preferably sealed with a resiliently actuated flap valve 20 controllable by the fingers of the operator and provided with a leather or rubber gasket.

10 As shown in Fig. 2, an article to be filled such as a pipe is held immediately under the opening of the discharge spout 19, the valve 20 is opened and the knob 18 rotated until a sufficient quantity of tobacco is discharged. The valve 20 is then closed and the interior chamber is efficiently sealed. During the dispensing operation the tobacco in the tube 16 prevents any substantial amount of air entering the dispenser.

20 To keep the tobacco in the desired moist condition, the filling plug 14 is made in the form of a cylinder of such size that it will retain a moist sponge. The top 14^a of this cylinder filling plug 14 is removable and is fitted with a fine mesh wire screen 14^b which allows the humid atmosphere of the sponge to pass through the tobacco and yet prevents the tobacco from passing into the sponge holder. It is to be understood that the filling cap or 30 chamber 14 effectively seals the interior of the chamber from the outside air, however, but is arranged to receive the sponge and provide an interior moistening means.

Figs. 4 and 5 are illustrative of slightly modified details of the dispensing means. Instead of a knurled knob, a crank handle 21 is attached to the worm shaft by means of a screw 22 for example. In this form, the pitch of the worm thread is of such size that a unit 40 amount of material may be dispensed at each revolution of the crank. For domestic storage of coffee, it would be arranged so that each turn of the crank would dispense a spoonful of coffee.

45 To seal the discharge opening 19 the cap 1 is provided with a gasket 2 which is cemented into the cap and remains permanently with it. The cap is hinged at the point 3 on a hinge pin supported in the pair of standards 4. A 50 flat spring 5 held in place by the pin 6 or any other means is doubled on itself and assembled under tension. This constant tension on the lobe or cam 7 formed on the end of the cap 1 will force the cap closed. When it is desired to open the cap, it is swung outwardly by the knob 8 until the flat surface 9 of the lobe 7 bears against the spring 5. The cap will then rest in open position until it is desired to close it again. This arrangement 60 gives a very positive snap action either open or closed and will act in the closed position to additionally seal the container.

In Fig. 6 a further modified form of dispensing means is shown in which the reservoir 65 is to be filled with some liquid such as alco-

hol or similar substance and it is desired to have a plunger valve in the end of the discharge opening. In combination with the glass container, the device would be ideally suited to dispense liquids or medicines of any preferred type and in which the knowledge of the actual amount in reserve is necessary. Such a construction prevents unsightly open bottles or reservoirs that collect dirt.

These various modifications of discharge 75 or dispensing devices are merely illustrative of various desirable forms to which the invention is adapted and which, due to various conditions of use or articles contained, might be desirable. It is also understood that these 80 enclosed products may effect the construction of the reservoir itself. For example, certain products of a corrosive nature could not be satisfactorily kept in a metallic container. Certain salts will seriously corrode metal and for protection, the reservoir and base might 85 all be of glass or the base might be of pulp, waxed paper or papier mâché. Such a construction would be materially cheaper than a special non-corrosive metal for the base. The 90 dispensing device could also be of glass.

Another important feature shown in Fig. 1 95 is the means for permanently sealing the glass dome to the base which is so essential for many articles. As shown, a ring of cork cemented to the lining is used and this is usually sufficient to compensate for the differences in coefficient of expansion of the glass dome and the metal base. However, it would be 100 possible to construct the rim of the base so thin that the metal itself will allow sufficient expansibility. This might be accomplished by spinning the metal into the rim portion or by stamping. A still further construction of the base to compensate in a measure for the 105 difference in expansion rate to prevent destruction of either the top or base would be by crimping the base rim to increase the peripheral expansibility. To keep the dome 110 permanently sealed is the essential requirement.

The term unit quantity as used herein, means such amounts as are commercially common. For example, the amount of sugar for sweetening coffee is figured in teaspoonfuls. 115 Therefore, for a cafeteria sugar dispensing machine, one rotation of the crank handle would be equal to one teaspoonful of sugar. Similarly, the amount of malted milk for a soda fountain drink or the amount of bromo-seltzer may be a tablespoonful and similarly one rotation of the crank in that type of machine would discharge the exact amount desired. For coffee, which it has been found, deteriorates upon exposure to air, the combination of the air tight, transparent container with a dispensing mechanism to dispense one 120 tablespoon of coffee per revolution of the crank, is very desirable. It is of course, obvious that in this modified form, the filling 125 130

plug is merely a screw threaded cap to satisfactorily close the bottom inasmuch as a moistening or other atmosphere modifier is not essential.

- 5 It is to also be noted that only when the material in the interior chamber is desired to be kept in a particularly moistened condition, will the sponge be kept therein. Some materials on the other hand, such as salt or plaster of Paris for dental use and similar products are desired to be kept in a dry atmosphere and a suitable absorbent material such as calcium chloride for example, will be placed in the cup like filling cap of Fig. 1.
- 15 If no changes in the general atmospheric conditions are necessary, the plain form of cap shown in Fig. 5 will be used.

While I have described several forms of embodiment of this invention, I am aware that various changes may be made by those skilled in the art and I, therefore, desire protection on a broad interpretation of the invention as disclosed and described herein and claimed in the claims appended hereto.

25 I claim:

1. In a tobacco humidor, a hermetically sealed glass reservoir, a base comprising a substantially cylindrical reservoir receiving section, a supporting section, a horizontal web therebetween through which the humidor is adapted to be filled, a tubular encased worm screw extending into said supporting section above the horizontal web, adapted to dispense the enclosed tobacco, and a spring controlled closure normally sealing said worm screw encasement.

2. In a tobacco humidor of the class described comprising a reservoir and a multiple section base, means to fill the reservoir through the base comprising a filling cap, said cap moistening means enclosed by and means over the moistening means to permit humid atmosphere to permeate the reservoir and to prevent contamination of the sponge by the enclosed product.

3. In an air-tight tobacco humidor of the class described comprising a multiple section base divided by a horizontal web, a transparent hermetically sealed reservoir attached thereto, a filling cap and moistening means received in the cap in said base to permit moisture to keep the tobacco in condition and to permit refilling of the reservoir, and a dispensing means connected to the upper section of said base and comprising a tubular casing worm screw therein, means thereon to turn the screw and remove the tobacco, and a closure valve to maintain said screw casing airtight.

60 4. In a dispensing machine of the class described comprising a multiple section base divided by a horizontal web, the upper section being adapted to receive a reservoir sealed thereto and a worm dispensing means to remove the enclosed product, the web be-

ing adapted to receive an atmosphere modifying closure and filling means, and the lower section being formed to receive the filling material when the machine is upside down.

5. In a dispensing machine of the class described comprising a base portion and a reservoir sealed thereto, the base portion being adapted to initially receive an enclosed product through a suitable filling opening and a dispensing means comprising a tubular casing, a worm thread therein, the pitch of the worm being such that one revolution thereof will discharge a unit quantity of the enclosed material, and a valve sealing the discharge opening.

70 6. In a dispensing machine of the class described comprising a base portion and a reservoir sealed thereto, the reservoir being adapted to be filled through the base portion and a dispensing means comprising a worm, 75 a casing covering said worm, a crank on said worm, and a valve positively closing said casing.

80 7. In a dispensing machine, a support comprising an entrance opening and a moisture modifying filling cap therein, a hermetically sealed transparent container attached to the support, and a means to dispense a unit quantity of the contents of said machine projecting into said support above the filling cap 85 and below the reservoir.

85 In testimony whereof I have affixed my signature to this specification.

ERNEST J. SWEETLAND.
